DESIGN FOR A LIGHTING FIXTURE

Morris B. Beck, Woodmere, N. Y.

Application February 25, 1933. Serial No. 47,314

Term of patent 14 years

To all whom it may concern:

Be it known that I, MORRIS B. BECK, a citizen of the United States, residing in Woodmere, Long Island, county of Nassau and State of New York, have invented a new, original, and ornamental Design for a Lighting Fixture, of which the following is a specification, reference being had to the accompanying drawing, forming part thereof.

I claim:

The ornamental design for a lighting fixture substantially as shown. MORRIS B. BECK.
